(Cl. D58—10)

To all whom it may concern:

Be it known that we, Earl E. Swanson and Rene Goudy, citizens of the United States and residents of the city and county of San Francisco and the city of San Mateo, county of San Mateo, respectively, State of California, have invented a new, original, and ornamental Design for a Milk Carton Tap, of which the following is a specification, reference being had to the accompanying drawing, forming part thereof.

Figure 1 is a plan view of a milk carton tap, showing our new design;

Figure 2 is a side elevation;

Figure 3 is an end view; and

Figure 4 is a front view thereof.

We claim:

The ornamental design for a milk carton tap, as shown.

EARL E. SWANSON.
RENE GOUDY.
